UNITED STATES PATENT OFFICE.

IWAO EGUCHI, OF TOKYO, JAPAN.

WATER-PILLOW.

1,381,067.

Specification of Letters Patent. Patented June 7, 1921.

Application filed December 27, 1917. Serial No. 209,189.

To all whom it may concern:

Be it known that I, IWAO EGUCHI, subject of the Empire of Japan, residing at No. 4 Kamimakicho, Nihonbashi-Ku, Tokyo, 5 Japan, have invented certain new and useful Improvements in Water-Pillows, of which the following is a specification.

My invention relates to improvements in water pillows, hot water bottles and like 10 articles and particularly to a device for closing the mouth of the bottle or pillow when in use.

According to the invention, the closing device comprises a frame in the form of a 15 parallelogram, the links of which are hingedly connected at the ends thereof, one of the links being provided with a clamping device such as a member carrying a set screw, adapted when the frame is in the closed or 20 collapsed position to engage another of the links to firmly clamp the same upon the mouth of the bottle or pillow.

The accompanying drawings illustrate an 25 example of a water-pillow constructed according to this invention, wherein:—

Figure 1 is a perspective view of the water-pillow, showing its mouth opened;

Figs. 2 and 3 are longitudinal partial sections of the same, Fig. 2 showing the mouth 30 closed, but before the closing device is clamped in closed position, while Fig. 3 shows the mouth of the pillow closed and sealed by the closing device;

Figs. 4 and 5 are detailed plans of the 35 closing device, Fig. 4 showing the frame opened, while Fig. 5 shows the same closed and its clamping device in clamping position.

The closing device which constitutes the 40 principal part of this invention, consists of a metal frame in the form of a parallelogram having four links 1, 2, 3, 4 the ends of which are hinged to one another, so that the frame forms varying parallelograms between the hinged points 5 and 6 when it is opened 45 (Fig. 4), and forms two parallel members consisting of the connected links 1 and 2 and the connected links 3 and 4 when it is closed (Fig. 5).

Carried on one of the longer links 1 of the 50 said frame is a clamping member 7 which has at one end a tubular part or boss 8 by which it is so attached that it may be freely turned

around the link 1 at the end thereof near the joint for the link 2, said member 7 having at its other end a lug 9 in which a set screw 10 is threaded.

The other longer link 3 of the said frame has on its outer surface near the joint for the link 4 a recess 11 adapted to be engaged by the pointed end of the said screw 10 when 60 the frame is closed and the clamping member is turned to embrace the links 1 and 3.

Thus, the closing device consisting of the 65 said frame and clamping member may be tightly closed by screwing up the said screw 10, so that the layers of material forming the mouth of the pillow or bottle and lying within the frame may be tightly pressed together, as shown in Fig. 5.

The closing device constructed as above 70 mentioned is arranged around the periphery of the mouth 14 of the pillow-body 12, and an outer mouth-piece 13 may be applied thereon to cover the links of the frame and hold the same in place, suitable notches 15 75 being made in the mouth-pieces above the frame, in order to permit the turning of the clamping member.

It will be seen that the closing device holds the mouth of the pillow wide open to permit 80 ready introduction of water, ice or the like thereinto, and also secures hermetical sealing of the mouth when it is closed.

I claim:

The combination with a flexible receptacle having a flexible neck with a plurality of notches provided in the mouth of the same, of a series of links surrounding said neck and having their ends pivotally connected together and forming a parallelogram, a locking member pivotally mounted on one of said links and provided with a locking screw adapted to engage another one of said links, and means provided on the last named link for receiving the end of 90 said screw, said locking member in locked position resting in the notches in the mouth of said receptacle.

In testimony whereof I affix my signature in presence of two witnesses.

IWAO EGUCHI.

Witnesses:

Den Kino,
Eishiro Abe.
